UNITED STATES PATENT OFFICE.

REUBEN M. ROSE, OF BROOKLYN, NEW YORK.

SEWING-MACHINE ATTACHMENT FOR DARNING; &c.

SPECIFICATION forming part of Letters Patent No. 235,456, dated December 14, 1880.

Application filed July 12, 1880. (No model.)

To all whom it may concern:

Be it known that I, REUBEN M. ROSE, of Brooklyn, in the county of Kings and State of New York, have invented a new and useful

5 Improvement in Attachments for Sewing-Machines for Embroidering, Fancy Stitching, and Darning Purposes, of which the following is a specification.

My invention relates to spring-pressure attachments adapted to admit of their being easily attached to and detached from the presser-bar or other portion of a sewing-machine, and organized to be raised or relieved by the action of the needle-carrier from pressure on the 15 material as the needle is withdrawn from the latter, and so as to permit the movement of the cloth or material by hand in various directions and to any desired distance, as the varying nature of the work to be done may require.

Such attachments have been made comprising a base-piece or socket adapted to be attached to the presser-bar or other part of the machine, and a rod or piece fitted in guides in 25 said base-piece or socket, having a foot at the lower end for pressing downward upon the material, and an arm near the upper end, through which the rod or piece is raised from the material when it is desired to shift the 30 latter.

The object of my invention is to simplify the construction of such attachments by reducing the number of parts of which they are composed, and also to afford the movable part 35 of such attachment a strong and adequate support.

To this end my invention consists in novel combination of parts, which is fully illustrated in the accompanying drawings, in which—

40 Figure 1 represents a side view of a portion of a needle-bar and presser-bar having my improved attachment secured thereto. Fig. 2 represents a transverse section of the presser-bar and a plan of the attachment. Fig. 3 represents a face view of the attachment. Fig. 4 represents a perspective view of the base-plate or stock-piece, and Fig. 5 represents a perspective view of the piece or plate adapted to slide or move in the ways or gibs of said base- 45 plate or stock-piece.

50 Similar letters of reference designate corresponding parts in all the figures.

A designates the presser-bar, to which, in this example of my invention, the attachment is secured, and B designates the needle-bar, 55 carrying the needle a.

C designates the base-plate or stock-piece of my attachment, to be secured to the presser-bar A, and here represented as having an angle-plate or angular projection, b, secured 60 to its back by riveting, fitting the presser-bar, as shown clearly in Fig. 2, and adapted to be secured by a screw, c.

In lieu of the form of projection here shown, the attachment may be provided with one to 65 fit the side of any presser-bar, or to fit in a slot in the end of the bar, or to be secured to the bar or to any part of the machine in any way.

The side edges of the base-plate or stock- 70 piece C are bent up or turned over, so as to form gibs or ways d, as shown clearly in Figs. 2 and 4, and a tongue at the top is provided with a hole, e, and bent over so as to form a guide, the use of which will be explained here- 75 inafter.

D designates the movable piece or plate fitting in the gibs or ways d, in which it is free to move longitudinally, and preferably corrugated at the center to increase its strength. 80 At the lower end the plate D is furnished with a tongue, bent outward at the bottom to form a presser-foot, f, which is perforated to permit the passage of the needle through it. At the upper end the plate D is furnished with a 85 tongue, which is inserted through the guide e and bent outwardly, so as to form an arm, g, for a projection, h, on the needle-bar B to strike against on its upward movement to raise the presser-foot f and release the material be- 90 ing operated on.

As represented clearly in Fig. 2, the arm g projects at a right angle to the plate D, while the foot f is bent to one side, so that when the attachment is set to allow the needle a to pass 95 through the perforation in the foot f the arm g will project on one side of the needle-bar. The arm g may be bent in any direction, to adapt the attachment for use upon machines in which the needle-bar is variously arranged 100 relatively to the presser-bar.

Around the tongue forming the arm g, below the guide e, is a coiled spring, i, which exerts a constant downward pressure upon the

presser-foot *f*, and the plate *D* has in it two slots, *j*, (see Fig. 5,) at the sides of the tongue which forms the arm *g*, into which the spring *i* fits, whereby I am enabled to get a long spring and still retain long bearings for the plate *D* in the gibbs or ways *d*.

It will be readily understood that the base-plate or stock-piece, with the gibbs or ways *d*, furnishes a broad bearing for the plate *D*, and thus affords adequate support to the latter, and that a simple and desirable attachment is produced, inasmuch as only three parts, exclusive of the spring, are required in its construction.

What I claim as my invention, and desire to secure by Letters Patent, is—

The combination of the base-plate or stock-piece *C*, having the fastening-projection *b*, gibbs or ways *d*, and guide *e*, the movable plate *D*, fitted loosely in said gibbs or ways, and provided with the presser *f* at its lower end, and the arm *g* projecting from its upper end, and a spring arranged to force said movable plate downward, substantially as described.

Witnesses: REUBEN M. ROSE.
